No. 757,129.

PATENTED APR. 12, 1904.

J. KRONE.

PIVOT GUN.

APPLICATION FILED JAN. 12, 1904.

NO MODEL.

UNITED STATES PATENT OFFICE.

JOHANNES KRONE, OF ESSEN-ON-THE-RUHR, GERMANY, ASSIGNOR TO
FRIED. KRUPP, AKTIENGESELLSCHAFT, OF ESSEN-ON-THE-RUHR,
GERMANY.

PIVOT-GUN.

SPECIFICATION forming part of Letters Patent No. 757,129, dated April 12, 1904.

Application filed January 12, 1904. Serial No. 183,678. (No model.)

To all whom it may concern:

Be it known that I, JOHANNES KRONE, a subject of the Emperor of Germany, and a resident of 56 Bismarckstrasse, Essen-on-the-Ruhr, 5 Germany, have invented certain new and useful Improvements in Pivot-Guns, of which the following is a specification.

The present invention relates to improvements in serving-steps for pivot-guns—that is 10 to say, guns in which the trunnions of the gun-barrel or of the cradle are mounted in a fork or the like, which is in turn rotatably mounted, by means of a vertical pivot, in a fixed carriage rigidly secured to the ground or to 15 the deck of a ship.

The object of my improvements is to provide a serving-step which is independent of the movement imparted to the gun during firing and at the same time is capable of following 20 the gun in its rotary or horizontal training movement. Serving-steps which rotate with the gun are already known; but the said steps have heretofore been rigidly connected with the trunnion-fork, and therefore took 25 part in the movement of the gun on firing, and thus rendered the serving of the gun difficult for the crew standing on the serving-step.

I attain the object of my invention by 30 constructing the gun substantially as illustrated in the accompanying drawings, in which—.

Figure 1 is a side view, partly in section, of a part of a gun embodying my invention. Fig. 2 represents one-half of a horizontal section 35 on the line 2 2, Fig. 1. Fig. 3 is a vertical section, on a larger scale, of the rotating bearing for the serving-step; and Fig. 4 is a modification of said bearing.

Referring to Figs. 1 to 3, the construction 40 of the gun-mount comprising pivot G and pivot-head A is well understood and needs no specific description. Mounted on the outer face of the pivot-head A, concentric with the pivot G, are an upper and a lower ring a', 45 which serve as ways for the larger ring B, rotatable around the pivot-head. The ring B is provided at its upper and lower edges with a number of rollers b', which are journaled in

rectangular projections b². A flange a² of the pivot-head serves as a runway for the lower 50 rollers, while the runway for the upper rollers is provided by a flat ring C, laid upon said rollers. The position of ring C relative to the upper rollers is maintained by means of the set-screws d, which are mounted in a ring 55 D of rectangular cross-section, rigidly connected with the pivot-head. The rotatable ring B has two arms E, which carry the serving-step F.

In order to impart horizontal rotary move- 60 ment from the gun to the serving-step, I provide a carrier g, connected with the trunnion-fork, the free end of which carrier extends downwardly into a slot e', formed in one of 65 the arms E and extending in the direction of recoil.

The mode of operation of my invention is as follows: When the gun is trained by rotation on its vertical pivot, the carrier g effects 70 at the same time the rotation of the serving-step around the pivot-head. The movement of the trunnion-fork, however, when the gun is fired is not imparted to the serving-step, because of the special arrangement of the same and because the carrier can move in the direc- 75 tion of recoil in the slot. The crew therefore is not hindered in the serving of the gun.

In the modification shown in Fig. 4 balls 80 are used instead of rollers in the bearing of the serving-step. The balls J run in grooves in the guide-rings H and in the reinforce- 85 ments of the rotatable ring B', which supports the serving-step. The position of the upper guide is secured in a way similar to that used in the roller construction by means of set-screws d. The arrangement of the serv- 90 ing-step and the carrier corresponds exactly to that described with reference to Figs. 1 to 3.

Having thus described the invention, the fol- 90 lowing is what is claimed as new therein:

1. In combination with a pivot-gun and its mount, a serving-step rotatably supported on said mount independently of the gun-pivot.
2. In combination with a pivot-gun mount 95 having a pivot-head upon which the gun ro-

tates, a serving-step rotatably mounted upon the pivot-head independently of the gun-pivot.

3. In combination with a pivot-gun mount having a pivot-head upon which the gun rotates, a serving-step rotatably mounted upon the pivot-head independently of the gun-pivot and means causing the serving-step to rotate with the gun in the horizontal traverse of the gun.

4. In a pivot-gun, the combination of the gun having a pivot, the mount having a pivot-head receiving the gun-pivot, a serving-step having rotary support on said mount, concentric with, but independent of the gun-pivot, and means for transmitting the horizontal traverse movement of the gun to the serving-step.

5. In a combination with a pivot-gun, having a suitable mount, a serving-step having rotary support independent of the gun-pivot, and means transmitting horizontal traverse movement of the gun to the serving-step, but permitting relative movement between the gun and step in the direction of recoil.

6. In a combination with a pivot-gun, having a suitable mount, a serving-step having a rotary support independent of the gun-pivot, and means transmitting horizontal traverse movement of the gun to the serving-step, but permitting relative movement between the

gun and step in the direction of recoil, and consisting of a carrier projecting from one of said parts and a slot on the other, in which the carrier engages, and which is elongated 35 in the direction of recoil.

7. In a pivot-gun, the combination of the gun and its mount, a serving-step having a rotary bearing on the mount independent of the gun-pivot, a carrier projecting downward 40 from the gun and a slot in said serving-step elongated in the direction of recoil to permit relative movement of the carrier in that direction, but fitting said carrier to cause transmission of rotary movement from the gun to 45 the step in the direction of horizontal traverse.

8. In a pivot-gun, the combination of the gun having a pivot, the mount having a pivot-head receiving said pivot, a ring surrounding 50 said pivot-head and having a rotary bearing thereon, a serving-step supported by said ring, and a connection transmitting rotary traverse of the gun to the serving-step.

The foregoing specification signed at Düs- 55 seldorf, Germany, this 16th day of December, 1903.

JOHANNES KRONE.

In presence of—

WILLIAM ESSENWEIN,
RUDOLPH LIEBER.
